UNITED STATES PATENT OFFICE

LEON B. MANSON, OF CORONA, NEW YORK, ASSIGNOR TO NOMA ELECTRIC CORPORATION, OF NEW YORK, N. Y., A CORPORATION OF NEW YORK

ORNAMENTAL DEVICE

Application filed April 24, 1929. Serial No. 357,660.

This invention relates to ornamental devices. It is directed to a decorative Christmas wreath provided with an electrical "candle" unit.

5 An object of this invention is to provide a wreath of the character described having improved means for rigidly supporting the candle simulating member.

10 A further object of this invention is to provide a neat, rugged, and highly decorative wreath of the character described which shall be relatively inexpensive to manufacture comprise few and simple parts easily assembled, and which shall yet be highly practical and efficient in use.

15 Other objects of this invention will in part be obvious and in part hereinafter pointed out.

20 The invention accordingly consists in the features of construction, combinations of elements, and arrangement of parts which will be exemplified in the construction hereinafter described, and of which the scope of application will be indicated in the following 25 claims.

In the accompanying drawing, in which is shown one of the various possible illustrative embodiments of this invention,

30 Fig. 1 is an elevational view of a Christmas wreath embodying the invention;

Fig. 2 is an enlarged transverse cross-sectional view of the core taken on the axis of the candle unit;

35 Fig. 3 is a fragment of a portion of a core section with part of the candle unit broken away to show the interior construction;

Fig. 4 is a fragmentary view of a portion of one of the core sections; and

40 Fig. 5 is a perspective fragmentary view of a portion of one of the core sections illustrating the supporting tongue construction for the "candle" unit.

45 Referring in detail to the drawing, 10 designates a Christmas wreath embodying the invention, here seen to comprise an annular body portion 11 and a candle simulating member 12.

Said body 11 comprises an annular core 13 made of a pair of complementary frame sections 14, 15 of semi-circular cross-section

55 maintained in assembled relation by an ornamental rope 16 wound around said core. Said sections 14, 15 may be made of heavy cardboard, papier-mâché or any other material suitable for the purpose described, and are provided with symmetrical registering V-shaped cut out portions 14^a, 15^a respectively at the inner edges 14^b, 15^b thereof respectively. When said frames are placed together, the cut outs 14^a, 15^a provide an opening 25 for receiving the candle simulating device 12.

60 Said device 12 comprises a hollow tubular member 17 made of cardboard or any other suitable material and colored and ornamented to simulate a candle. Secured within the upper end portion 18 of said tubular member 17, is a lamp socket 19 for receiving the base 20 of a tapered colored lamp 21 simulating a candle flame. The lower end portion 22 of said tubular member 17 is inserted within said opening 25, said tube projecting 65 radially toward the center of the wreath.

70 For rigidly supporting the tubular member 17 and to prevent looseness or movement of said member, a tongue or tab 26 is secured to one section 14 adjacent the outer edge 14^b thereof, in alignment with the opening 25. Said tongue 26 may comprise a separate piece 27 having a portion 28 fastened as by clips or stitching 29 to the inner surface of said frame section member 14. A 75 backing member 30 of cloth, adhesive, tape, or any other suitable material may be pasted to said tongue to strengthen the same. The tongue 26 projects upwardly into the tubular member 17 thru the lower end thereof, the side edges of said tongue frictionally engaging the interior surface of said tube for securely retaining said tubular member in upright position and to prevent looseness thereof.

80 Although the tab 26 is shown as a separate piece secured to the frame section 14, it will be understood that said section and tab portion may be made of one piece as from a single blank of cardboard pressed into the desired shape, said tab being bent upwardly for projection into the hollow of the tube 17.

85 Electrical conductor wires 31, 32 attached to the central contact 33 and shell portion 34

respectively of the lamp socket 19 form a duplex cable 35 extending downwardly thru the tube 17 and out between the frame members 14, 15. Said cable may be tied into a knot 36 close to the core 13 to prevent movement of the cable within said tube 17. Said cable 35 may terminate in an attachment plug 38 for connection to a source of electric power.

10 The body 11 may be provided at the top portion thereof with a loop 40 for suspending said wreath, and an ornament 41 may be secured to said body 11 in any suitable manner adjacent the illuminating device 12 to enhance the decorative effect.

15 It will thus be seen that there is provided a device in which the several objects of this invention are achieved, and which is well adapted to meet the conditions of practical use.

20 As various possible embodiments might be made of the above invention, and as various changes might be made in the embodiment above set forth, it is to be understood that all 25 matter herein set forth or shown in the accompanying drawing, is to be interpreted as illustrative and not in a limiting sense.

Having thus described my invention I claim as new and desire to secure by Letters 30 Patent:

35 1. In a wreath of the character described, a hollow core having an opening, a candle simulating member extending into said opening and projecting toward the center of the wreath, and means within said core for supporting said member, said means comprising a member attached to said core and projecting into the lower end of said tubular member.

40 2. In an ornamental device, an annular member of substantially semi-circular cross-section having a tongue member integral therewith and extending from the outer edge portion thereof, and a tubular member receiving said tongue thru one end thereof, said annular member having a cut-out portion adjacent the inner edge portion thereof and in alignment with said tongue for receiving an intermediate portion of said tubular member.

45 3. A wreath comprising a pair of annular complementary sections of semi-circular cross-section, adapted to be fitted together to form an annular core, said sections having symmetrical cut-out portions registering to form an opening, and a candle simulating tubular member extending into said core thru said opening, one of said sections having an upstanding projection extending into the lower end of said tube.

50 4. A wreath comprising a pair of annular complementary sections of semi-circular cross-section adapted to be fitted together to form an annular core, said sections having symmetrical cut-out portions registering to

form an opening, and a candle simulating tubular member extending into said core thru said opening, one of said sections having an upwardly extending tab portion projecting into the lower end of said member, a lamp socket secured within the upper end portion of said member and conductor wires secured to said socket and extending downwardly thru said tubular member.

55 5. A wreath comprising a pair of annular complementary sections of semi-circular cross-section, adapted to be fitted together to form an annular core, said sections having symmetrical cut-out portions registering to form an opening, and a candle simulating tubular member extending into said core thru said opening, one of said sections having an upwardly extending tab portion projecting into the lower end of said member, a lamp socket secured within the upper end portion of said member and conductor wires secured to said socket and extending downwardly thru said tubular member, said conductors being tied in a knot adjacent the undersurface of said core.

60 6. A wreath comprising a pair of annular complementary sections of semi-circular cross-section, adapted to be fitted together to form an annular core, said sections having symmetrical cut-out portions registering to form an opening, a candle simulating tubular member extending into said core thru said opening, and means disposed on an outer portion of the interior of said core engaging the end of said member.

65 In testimony whereof I affix my signature.
LEON B. MANSON.
